UNITED STATES PATENT OFFICE.

HENRY E. RINGLE, OF BREMEN, INDIANA, ASSIGNOR OF ONE-HALF TO OLIVER E. DIETRICH, OF BREMEN, INDIANA.

BROODER.

1,134,229.

Specification of Letters Patent. Patented Apr. 6, 1915.

Application filed October 4, 1910. Serial No. 585,208.

To all whom it may concern:

Be it known that I, HENRY E. RINGLE, a citizen of the United States, residing at Bremen, in the county of Marshall and State 5 of Indiana, have invented certain new and useful Improvements in Brooders, of which the following is a specification.

My invention relates to poultry brooders.

An important object of this invention is 10 to provide a poultry brooder of such improved construction that chickens or other domestic fowls may be reared with small trouble and expense.

A further object of this invention is to 15 provide a poultry brooder formed of readily separable parts, whereby the brooder may be easily and thoroughly cleaned.

A further object of this invention is to 20 provide apparatus of the above character, which is simple in construction, cheap to manufacture, and reliable in its operation.

Other objects and advantages of this invention will be apparent during the course 25 of the following description.

In the accompanying drawings forming a part of this specification, and in which like numerals are employed to designate like parts throughout the same, Figure 1 is a perspective view of the brooder, the same being provided with the outdoor cover, Fig. 2 is a transverse vertical section through the same, Fig. 3 is a perspective view of the brood-cover, and, Fig. 4 is a perspective view of the brooder, employing an indoor cover, and the parts thereof being separated and disposed in proper positions to be assembled.

In the drawings, wherein is illustrated a preferred embodiment of my invention, the numeral 1 designates a preferably rectangular lamp-box or furnace, having a top 2 formed of sheet metal. The inner surfaces of the sides of the lamp-box 1 may be lined with a suitable fire-proofing material, such 40 as asbestos, as shown at 3 in Fig. 2. The forward side 4 of the lamp-box 1 is provided with an opening formed therethrough, as shown, which opening is normally closed by a vertically swinging door 5, having connections with the side 4 by means of hinges 6. This door has its lower edge terminating in a plane upwardly of the lower edge of the side 4, as shown, whereby an opening 7 is provided for the passage of air into the 55 lamp-box to a lamp 8 disposed therein. This

lamp is preferably arranged centrally of the lamp-box 1 and may be of any well known or preferred type. The forward side 4 may preferably be provided with openings 9 formed therethrough, for supplying air to 60 the lamp. The lamp-box 1 is provided upon its longitudinal side opposite side 4, with a stack 9^a for discharging the products of combustion given out from the lamp. A hot-air space or chamber 10 is provided above 65 the lamp-box 1, the sheet metal top 2 forming the bottom wall of the hot-air chamber. Strips 11 are suitably connected with the upper portion of the lamp-box 1 and form the side walls of the hot-air chamber 10. 70 The transverse strips 11 are provided with openings 12 formed therethrough to admit of the passage of cold air into the hot-air chamber 10.

Disposed above the hot-air chamber 10, is 75 a box-like structure 13, having a bottom 14 formed of wood or some other material which is a relatively poor conductor of heat. This bottom 14 engages the strips 11 and equal portions of said bottom extend on 80 either side beyond the transverse strips 11. Suitably secured to the lower surface of the bottom 14, are pairs of transverse spaced lugs 15, adapted to fit snugly between the transverse strips 11 and prevent the accidental displacement of the box structure 13 with relation to the lamp-box 1, yet permitting of the same being separated when desired. The box structure 13 has its forward side 16 removable, the same being slidably mounted between spaced strips 17 suitably secured to the forward ends of end pieces 18. The forward side 16 is provided with spaced openings 19, which lead into compartments 20 formed by providing the 95 box structure 13 with a central transverse partition 21. This transverse partition is preferably formed of metal and is removable from the box structure. The rear end of this partition is loosely mounted within a vertical groove 22^a formed upon the inner surface of the rear side of said box structure and the forward end of this partition is loosely mounted within a vertical groove 22 upon the inner surface of the forward side 16 and midway of the ends thereof. The openings 19 are provided so that the chickens may enter or leave the compartments 20 and such openings are normally closed by doors 23. These doors are adapted to be opened 100 105 110

by swinging in a substantially vertical plane and are connected with the forward side 16 by means of hinges 24. Each of the doors 23 may be retained in its open or elevated 5 position by means of coöoperating hook and eye members 25 and 26, respectively, which are suitably secured to said forward side 16 and door. The bottom 14 is provided with suitably spaced openings 27 (see Fig. 2) 10 within which are disposed the lower ends of vertical tubes or posts 28. As shown in Fig. 4, there is a group of these tubes within each of the compartments 20. An important function of these tubes is to conduct hot air 15 from the chamber 10 into the upper portion of the compartment 20.

Within each of the compartments 20 is arranged a brood-cover 29, shown more clearly in Fig. 3. This brood-cover comprises an open rectangular frame 30 upon which is suitably mounted a section of transparent material 31. To the frame 30 is suitably secured side curtains 32, provided with vertical slits 33, whereby the chickens 25 may easily pass into and out of the brood-cover. The frame 30 is supported by metallic legs 34 suitably connected to the corners thereof as shown. As illustrated in Fig. 2, the brood-cover 29 is disposed above 30 the tubes 28. An important function of the brood-cover is to prevent the escape to a certain extent, of the hot air delivered from the tubes 28. The chickens in the compartment 20, if becoming chilled therein, may 35 go into the brood-cover where they will be warmed.

In order that the chickens may easily and safely enter the compartments 20 through the openings 19, an inclined platform 35 is 40 provided, having its inner edge beveled as shown at 36 in Fig. 2. This platform is detachably connected with the box structure 13, by means of hook and eye members 37 and 38, secured respectively, to said box 45 structure 13 and platform 35. As illustrated in Fig. 4, an indoor cover 39 is provided for the box structure 13, which cover comprises an open rectangular frame 40 divided by a central transverse partition 41 into compartments 50 corresponding to the compartments 20. The rectangular frame 40 has suitably secured thereto sections of wire gauze 42 or the like. Any suitable means may be employed for detachably holding the cover 39 55 upon the box structure 13.

When the brooder is used out of doors, the cover 39 may be dispensed with, and an outdoor cover 43 employed in its place. This outdoor cover comprises approximately 60 segmental-shaped end pieces 44 having their rear ends connected by a longitudinally disposed strip 45 and their forward ends connected by an open frame-work 46. The openings of this frame-work are covered by 65 sections of wire gauze 47. The lower por-

tion of this outdoor cover is provided with a rectangular flange 48 adapted to snugly receive the upper end of the box structure 13. Corresponding ends of the outdoor cover 43 and the box structure 13 are provided respectively with coöoperating hook and eye members 49 and 50, which detachably secure said outdoor cover to said box structure. The cover 43 further comprises a normally inclined lid 51, having a sheet 70 metal cover 52 arranged upon the outer side thereof. This lid 51 is hinged to the frame-work 46, as shown at 53. From the description of the above referred to parts, it is obvious that this lid may be swung upwardly whereby access may be had to the interior of the compartments 20. An awning 54 has its upper longitudinal edge suitably secured to the upper portion of the frame-work 46 and has its lower longitudinal edge 80 suitably secured to a cylindrical rod 55. Each of the end pieces 44 is provided with a pivoted socket-member 56 through which is longitudinally adjustably mounted a support-rod 57, having its outer end looped for forming a socket for rotatably holding one end of the rod 55. The socket-member 56 carries a clamping nut 58, whereby the supporting-rod 57 may be locked thereto in a desired position. The function of the awning 54 is to regulate the amount of cold air which enters the compartments through the frame-work 46, and also to prevent the entrance of rain into said compartments.

In the use of the chicken brooder I cover 100 the bottom 14 with sand, which I find prevents the heat of said bottom from causing disease among the chickens. Special attention is called to the fact that the lamp-box 1, the box structure 13, and the cover are 105 readily separable, which permits of these parts being cleaned or repaired. It is also worthy of note that a decided advantage is gained in having the forward side 16 removable, which permits of a thorough and easy 110 cleansing of the walls of the compartments 20.

I wish it understood that the form of my invention herewith shown and described, is to be taken as a preferred example of the 115 same, and that certain changes in the shape, size and arrangement of parts may be resorted to without departing from the spirit of my invention or the scope of the subjoined claim.

Having thus fully described my invention what I claim as new and desire to secure by Letters Patent, is:—

In a chicken brooder of the character described, the combination with a lamp box, of a section of sheet metal attached to the upper portion of the lamp box at a point near and spaced from the upper end thereof for providing above the section of sheet metal a hot air chamber having air inlets, a box- 120

structure to be mounted upon the upper end of the lamp box and longer than the same to extend beyond the lamp box at both ends for equal substantial distances, a central transverse partition dividing the box-structure into two compartments, hot air inlets leading into the compartments and passing through the bottom of the box-structure and having communication with the hot air chamber, and transverse strips secured to the lower surface of the box-structure in parallel spaced relation to removably enter the hot air chamber and engage with their sides, the inner walls of the transverse por-

tions of the lamp box and with their ends 15 the longitudinal portions of the lamp box, whereby the box-structure is held against improper longitudinal and lateral movements with relation to the lamp box but may be readily separated therefrom by upward movement with relation thereto. 20

In testimony whereof I affix my signature in presence of two witnesses.

HENRY E. RINGLE.
